2 Claims. (Cl. 250—27)

Our present invention relates to receiving circuits, and, more particularly, to high frequency amplifiers free from self-oscillation.

When using, for example, a receiver comprising one or more stages of high frequency amplifiers, a detector and one or more low-frequency amplifiers, and, particularly, when receiving short waves, the drawback is encountered that the high frequency stages react on each other and 10 on the detector. This is due to the fact that when one of the two filament leads is connected to the anode current source, the other one has still a given alternating current potential relatively to the first mentioned lead owing to the 15 impedance of the filaments. It is because of this lead that oscillations of a high frequency amplifier are passed on to following high frequency stages, if any, and the detector.

In receiving circuit-arrangements which include in the anode circuit of a detector valve bypass condensers for conducting back the high frequency oscillations to the cathode, it is already known to use two condensers of like size which are connected respectively to either of the poles 25 of the filament and on the other hand to the anode.

In the case of discharge tubes having an indirectly heated cathode, which cathode is connected to the centre of a potentiometer connected in 30 parallel to the filament, it has been found, particularly when more than one high frequency amplifier is used, that the coupling above referred to may occur.

Accordingly, it is one of the main objects of 35 the present invention to provide a radio installation, and, more particularly, a radio receiving circuit comprising two or more discharge tubes, the filaments of which are supplied from a common source of current, free from undue coupling 40 by the use of a simple and novel means.

Another important object of the invention consists in connecting in parallel, or in series, or both in parallel and in series, with the filament leads between two or more of the valves in which high 45 frequency currents occur, reactances of such size that any coupling between these valves along the said leads is avoided.

Another object of the invention consists in providing an amplifier comprising a plurality of 50 discharge tubes having an indirectly heated cathode, each of said cathodes being connected to the centre of a potentiometer connected across the filament, in which a condenser is mounted between the centre of the said potentiometer and one or both of the filament leads.

The novel features which we believe to be characteristic of our invention are set forth in particularity in the appended claims, the invention itself, however, as to both its organization and method of operation will best be understood 60 by reference to the following description taken in connection with the drawing in which we have indicated diagrammatically several circuit organizations whereby our invention may be carried 65 into effect.

The invention will be more clearly understood by reference to the accompanying drawing in which two embodiments thereof are illustrated.

Fig. 1 shows part of the diagram of a receiving set having two high frequency amplifiers, a detector and a low frequency amplifier. 70

Fig. 2 shows diagrammatically the present invention embodied in a discharge tube having an indirectly heated cathode.

Referring to Fig. 1, the part of the diagram of 75 a receiving set which is associated with the supply of the filaments of the discharge tubes is shown. The filaments 3, 4, 5 and 6 respectively of two high frequency amplifiers, a detector and a low frequency amplifier are supplied from a storage battery (not shown) or similar source of 80 current.

The lead 1 is connected to an anode battery 9. Since the high frequency currents in the anode 85 circuits of the high frequency amplifiers and the detector will make their way through the cathodes of the said valves, and only the filament lead 1 is connected to the anode battery, the filament lead 2, owing to the impedance of the filaments which are connected in parallel, will be at a given 90 alternating current potential relatively to the first mentioned lead. By bridging by a condenser 7 the filament leads between the tapping points of the filaments 3 and 4, the alternating current potential across the lead 2 will be neutralized, 95 and thus a mutual coupling of the two high frequency amplifying valves will be avoided.

It is of course highly inconvenient that the high frequency oscillations which might be generated in the lead 2 are capable of propagating towards 100 the detector and the low frequency amplifier. In accordance with the invention this inconvenience may be entirely obviated by connecting a high frequency choking coil 8, of low ohmic resistance, in the part of the filament lead 2 between the 105 tapping points of the cathodes 4 and 5.

Fig. 2 shows a feeding diagram of a discharge tube having an indirectly heated cathode 11. The filament 10, enclosed within the said cathode, 110 is fed through the above mentioned leads 1 and 2.

In addition, the cathode 11 is connected, by means of a lead 15, to the centre of a potentiometer 12, mounted in parallel to the filament 10.

It has been found that when more than one high frequency stage is used, the alternating current potential existing between the lead 15 and the filament leads may give rise to undue couplings between the said valves.

In accordance with the invention a by-pass condenser 13 is interconnected between the lead 15 and the filament lead 2. Although not essential, the lead 15 and the filament lead 1 may likewise have connected between them a condenser 14 so as to ensure entire symmetry.

15 While we have indicated and described several systems for carrying our invention into effect, it will be apparent to one skilled in the art that our invention is by no means limited to the particular organizations shown and described, but that many modifications in the circuit arrangements, as well as in the apparatus employed, may be made without departing from the scope of our invention as set forth in the appended claims.

What we claim is:

25 1. In combination with a source of uni-directional heating current, a plurality of filaments

of high frequency amplifiers connected in parallel, a filament of a detector in parallel with the said filaments, at least one condenser connected in parallel between two of the high frequency amplifiers to prevent high frequency coupling between the said two amplifiers, and a high frequency choke connected in series between the said detector filament and the next preceding amplifier filament.

2. In combination with a source of heating current having positive and negative terminals, a detector and an audio frequency amplifier having heated elements connected in parallel across said terminals, a radio frequency choke coil having a low ohmic resistance and the heated element 85 of a radio frequency amplifier connected in series across the terminals of the detector heated element, one end of said choke coil being directly connected to the positive terminal of said detector heated element, a source of anode potential 90 and a lead connecting the negative terminal of said last named source to the negative terminal 95 of the heated element of said radio frequency amplifier.

KLAAS POSTHUMUS.
